UNITED STATES PATENT OFFICE.

JAMES W. DANDRIDGE, OF GARRISON, WEST VIRGINIA.

STENOGRAPHER'S TRANSCRIPT RACK.

Application filed April 13, 1921. Serial No. 462,412.

To all whom it may concern:

Be it known that I, JAMES W. DANDRIDGE, a citizen of the United States, residing at the city of Garrison, in the county of Boone 5 and State of West Virginia, have invented certain new and useful Improvements in Stenographers' Transcript Racks, of which the following is a specification.

The object of my invention is to provide 10 an improved transcript rack for stenographers and typewriting machine operators, for holding in a desired position a stenographer's shorthand notes, copy or manuscript properly spread out so as to enable 15 the operator to easily and efficiently transcribe from shorthand or from copy or manuscript on a typewriting machine, a copy therefrom.

The principles of my invention are illustrated 20 in the drawings in which—

Figure 1, is a side elevation showing the rack in use.

Figure 2, is a rear elevation of the device.

Figure 3, is a sectional view taken on the 25 line 3—3 of Figure 2.

Figure 4, is a detailed sectional view of the extension bar.

A represents the base constructed preferably of wood of sufficient dimensions to 30 allow a type writing machine to rest thereon whenever it is desirable to operate my device. B represents the foot plate attached to the base by hinges F, F, upon which the metal pipes C, C, are fixed preferably over perpendicular pivots D extending upward interiorly into the feet of the pipes C, C, the pivots being held secure by clamps E, E to the foot plate B by screws or by suitable means. G represents the lever revolving 40 freely at its outer end on a pin H attached to the projection I of the base, it may be turned to the right or to the left and made tight to the upper surface of the foot plate B by the screw bolt K. C, C, in Figure 2

45 represent the metal pipes firmly fixed over perpendicular pivots D, D secured to the clamps E, E, on the foot plate B. M represents the pipes adapted to move up or down within the pipes C, C so as to attain a desired 50 elevation being bent forward at the upper ends with arms to receive the extension bars T, the desired elevation is made secure by screw bolts L. N represents the swivel rest at the upper end of the pipes M, M. The 55 extension bars may have slight sliding in arms M so as to bring the rest board a little

nearer to or farther from the operator and be adjusted at any angle desired. P represents the rest board constructed of suitable material of sufficient dimensions to hold the 60 paper from which a copy is to be made and having attached thereto a pivot U, a swivel rest N held thereto by means of clamps made secure to the rear of the rest board. O represents the clip securely fastened to the rest 65 board P for holding the copy or manuscript in place. Q represents the clamps secured to the rear of the rest board by screws or other suitable means and having attached thereto swivel rests N. R represents a typewriting machine placed on the base A. S represents the cross pipes securely fastened to the perpendicular pipes C, C, and M, M, so as to give firmness and strength to the 70 frame as shown in Figure 2. T represents the extension sectional bars that may be slightly pushed in or pulled out of the arms at the upper ends of the pipes M, M for the purpose of shortening or lengthening the 75 distance of the rest board P from the operator as may be desired. U represents the pivot having securely fastened thereto the swivel rest N which may be pulled out of the sectional extension bars at will and inserted in the upper ends of the forward projecting arms of the pipes M, M.

In practice my device may be operated as follows:

When my device is not in use the sectional extension pipes T may be withdrawn from 90 the pipes M, M and the rest board P laid flat on the upper surface of the base A. The screw bolt K may be loosened and the lever G pushed aside and the perpendicular pipes C, C, M, M, turned over and laid on the 95 rest board P. The device may then be placed in a convenient spot and will not occupy much space. When it is desired to use the device, take it out, raise the pipes C, C, M, M, in a perpendicular position and bring the 100 lever G over the foot plate B and tighten it by turning the screw bolt K, then insert the sectional extension bars T into the arms at the upper ends of the pipes M, M, raise or lower the pipes M, M, into the pipes 105 C, C, at the elevation desired, adjust the section extension bar by pulling out or pushing in until the desired distance is attained, place the type writing machine on the base A, fasten the manuscript or copy under the 110 clip O at the top of the rest board P and adjust the rest board by means of the swivel

rest N at the perpendicular or at any angle desired and my device is ready for use.

What I claim and desire to secure by Letters Patent of the United States, is—

5 In a stenographer's copy holding rack comprising a rest board and clip for holding the copy secure thereon, the combination of a supporting frame composed of two upright pipes held in spaced relation on a supporting base, two telescoping pipes supported in and vertically movable in said upright pipes, both sets of pipes being respectively braced by cross bars which are fastened to

and extend between the said upright pipes and between the two telescoping pipes to 15 firmly hold each set respectively in fixed relation, a foot plate resting on and hinged to the supporting base and forming a seat for the two upright pipes, a lever or clamp pivoted to the supporting base and provided 20 with an overhanging head or neck to fit over the foot plate and provided with a set screw for clamping the foot plate in position, all substantially as described.

In testimony whereof I affix my signature. 25
JAMES W. DANDRIDGE.
